Primary Examiner — Richard Kearney*Assistant Examiner* — Liv C Anderson(74) *Attorney, Agent, or Firm* — Notaro, Michalos & Zaccaria P.C.(57) **CLAIM**

The ornamental design for a security solar light, as shown and described.

DESCRIPTION

FIG. 1 is a front perspective view of a security solar light showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines in the figures depict portions which form no part of the claimed design. The dash-dot-dot broken lines in the figures represent a boundary of the claimed design and form no part thereof.

1 Claim, 7 Drawing Sheets(56)
